UNITED STATES PATENT OFFICE.

DAVID B. DONALDSON, OF DUNMORE, PENNSYLVANIA, ASSIGNOR OF
ONE-HALF TO EVAN F. DAVIS, OF DUNMORE, PENNSYLVANIA.

KNIFE OR SCISSORS SHARPENER.

SPECIFICATION forming part of Letters Patent No. 794,854, dated July 18, 1905.

Application filed March 1, 1905. Serial No. 247,926.

To all whom it may concern:

Be it known that I, DAVID B. DONALDSON, a citizen of the United States, residing at Dunmore, in the county of Lackawanna and State 5 of Pennsylvania, have invented a new and useful Knife or Scissors Sharpener, of which the following is a specification.

This invention relates to devices for sharpening carving and "butcher" knives, scissors, 10 and like implements requiring a coarse cutting edge and which may also be employed for sharpening scythes, reaping-hooks, cradle-blades, grass-cutters, and similar implements, and has for its object to simplify and improve 15 the construction and increase the efficiency and scope of devices of this character.

With these and other objects in view, which will appear as the nature of the invention is better understood, the same consists in certain 20 novel features of construction, as hereinafter fully described and claimed.

In the accompanying drawings, forming a part of this specification, and in which corresponding parts are denoted by like designating 25 characters, is illustrated the preferred form of embodiment of the invention capable of carrying the same into practical operation, it being understood that the invention is not necessarily limited thereto, as various changes 30 in the shape, proportions, and general assemblage of the parts may be resorted to without departing from the principle of the invention or sacrificing any of its advantages.

In the drawings thus employed, Figure 1 is 35 a side elevation of the improved device arranged as a knife-sharpener, and Fig. 2 is a plan view showing the device arranged as a scissors-sharpener. Fig. 3 is an end elevation with the device arranged as a knife-sharpener. 40 Fig. 4 is an end view of the abrading members arranged as a scissors-sharpener.

The improved device consists of two drum-like members 10 11, disposed side by side and provided with V-shaped ribs 12 13, arranged 45 spirally thereon from end to end. The drum

members are mounted for rotative adjustment upon studs 14 15, which are supported in spaced transverse apertures extending through a vertical standard 16, the latter supported in turn from a base 17, of any approved form. The 50 studs are connected at their outer ends by a yoke or link 18, the link having a transverse aperture at one end for receiving one of the studs and with an open slot 19 for detachably engaging the other stud. The opposite ends 55 of the studs 14 15 are threaded and provided with wing-nuts 20 21, bearing against the outer face of the standard 16, by which means the spirally-ribbed drums are firmly clamped in position. By this simple arrangement an effective abrading implement is produced which will very quickly produce a cutting edge upon the blade (represented at 22) when the latter is drawn longitudinally of the drums and transversely of and in contact with the sharp edges 60 of the V-shaped spirally-disposed ribs and with the cutting edge between the drums at their contact-points.

One of the drums is formed with one side flattened, as at 23, to provide a rest for the 70 blades of a pair of scissors or shears, as illustrated in Figs. 2 and 3, or any other implement having a similarly-formed cutting edge.

The drum members are of hardened steel, and when one part of the ribs becomes worn 75 and "dull" a slight rotative adjustment will bring new and "sharp" portions into position, and thus quickly renew the device, and these adjustments may be repeated until the whole surface of the ribs has been worn dull. The 80 total lengths of the spiral ribs are thus utilized for producing the required abrasive effect, and as required adjustments are relatively small each time the "life" of the device will be prolonged to a corresponding extent.

The device is simple in construction, effective in action, and can be readily adapted, as above noted, for any of the various forms of blades requiring a coarse cutting edge. 90

Having thus described the invention, what is claimed is—

A knife and scissors sharpener comprising two drums arranged side by side and provided with V-shaped ribs disposed spirally thereon from end to end, and one of said drums flattened on one side, and means for rotatively adjusting said drums.

In testimony that I claim the foregoing as my own I have hereto affixed my signature in the presence of two witnesses.

DAVID B. DONALDSON.
